Primary Examiner—James M. Gandy*Assistant Examiner*—Marcus Jackson*Attorney, Agent, or Firm*—Kane, Dalsimer, Sullivan, Kurucz, Levy, Eisele & Richard**[57] CLAIM**

The ornamental design for a sign, as shown and described.

DESCRIPTION

FIG. 1 is a front elevational view of a sign showing my new design, with the rear being flat and unornamented and with the article being of no substantial thickness; and,

FIG. 2 is a front elevational view of a second embodiment thereof, wherein the only difference resides in the information on the sign.

FIG. 1

FIG. 2
